CLAIM

The ornamental design for a seating product, as shown and described.

DESCRIPTION

FIG. 1 is a front perspective view of the seating product according to a preferred embodiment.

FIG. 2 is a rear perspective view of the seating product.

FIG. 3 is a front elevation view of the seating product.

FIG. 4 is a left elevation view of the seating product.

FIG. 5 is a rear elevation view of the seating product.

FIG. 6 is a right elevation view of the seating product; and, FIG. 7 is a top plan view of the seating product.

The broken line disclosure includes trim on the outside edges of the seat and backrest; stitching on the top of the seat and the rear of the backrest; the oval on the front of the backrest; and the structural portions of the seating product is for illustrative purposes only and form no part of the claimed design.
